UNITED STATES PATENT OFFICE

JAMES S. DOUGLASS, JR., OF CANANDAIGUA, NEW YORK

HEATING SYSTEM FOR AUTOMOBILES AND COUPLING THEREFOR

Application filed September 24, 1928. Serial No. 307,802.

This invention relates to a steam heating system in which the waste heat from the exhaust gases of the internal combustion engine in combination with water from the cooling system of the engine is utilized to generate superheated steam which is then passed through suitable radiators to heat the inside of the automobile and the object of this invention is to reduce such a heating system to its simplest form in which it will operate efficiently.

Another object of the invention is to provide attachments by which the connections between the steam heating devices and the exhaust pipe on the engine of the automobile can be easily and cheaply made.

These and other objects of the invention will be fully illustrated in the drawings described in the specification and pointed out 20 in the claims at the end thereof.

In the drawings:

Figure 1 is a diagrammatic side elevation of a portion of an automobile illustrating the application of my steam heating system 25 thereto.

Figure 2 is an enlarged longitudinal sectional view of the steam generator of my heating system and the connections by which it is mounted in the exhaust pipe of the 30 engine.

Figure 3 is a vertical section on the line 3x, 3x of Figure 2.

Figure 4 is a top plan view of Figure 2.

Figure 5 is a bottom plan view of Figure 2. 35 Figure 6 is a top plan view of a modification of Figure 2 showing one inlet water tube and two outlet steam tubes, each of which is adapted to feed a separate radiator.

Figure 7 is a vertical longitudinal section 40 corresponding to Figure 2 showing a modified form of one of the steam tubes.

Figure 8 is a transverse section on the line 8x, 8x of Figure 7.

Figure 9 is a vertical longitudinal section 45 corresponding to Fig. 2 showing one inlet water tube and four outlet steam tubes.

Figure 10 is a vertical section on the line 9x, 9x of Figure 9.

In the drawings like reference numerals 50 indicate like parts.

The heating system forming the subject matter of this invention takes water from the water circulating system of the car, changes it into superheated steam by using the heat of the exhaust gases of the automobile engine of the car. This superheated steam is then passed through one or more radiators in the car for the purpose of heating the car. The superheated steam is condensed into water by the radiators and this water is then returned to the circulating system of the car so that no water is lost from the car. The water is thus used over and over again both for cooling the engine and for heating the car and it is used without waste.

As shown in Figure 1, water is drawn by the pipe 1 from the pipe 2 which is part of the water circulating system of the car. The water is forced into the pipe 2 under pressure by the water circulating pump of the car. The pipe 1 first leads up to the dash where it connects with a valve 1A which controls the flow of water through it. This valve is preferably a needle valve. By opening this valve a slight amount, only a small amount of water will pass and this will make superheated steam by which the car will be heated. If the valve is open wide a large amount of water will pass which will be heated and will pass through the radiator not as steam but as water to heat the car. From this valve 1A the water flows down through the pipe 1. The heater described herein is either a steam or hot water heater depending on the setting of the valve 1A on the dash. One side of the U shaped tube 3 is mounted in the exhaust manifold of the engine, where it is subjected to a high temperature of the exhaust gases of the engine. The other side of the U shaped tube 3 is connected to a pipe 4 which leads to one or more radiators in the car, to which radiators superheated steam is supplied for the purpose of heating the car.

The U shaped tube 3 is mounted in the saddle block 5 shown in Figure 2.

The exhaust pipe is provided with a large hole or opening 6 therein and is big enough to permit the insertion of the U shaped tube 100

3. Between the block 5 and the exhaust pipe 7 a strip of asbestos or other suitable packing material 8 is provided by which the joint between the block 5 and the opening in the exhaust pipe 7 may be securely sealed. A washer 9 is placed on the pipes 1 and 4. The cap 10 makes threaded engagement with the block 5 and screws down on it carrying the washer 9 with it. The pipes 1 and 4 are connected to the ends of the U by enlarged joints and these joints are clamped between the washer 9 and block 5, thus securely holding the pipes in place.

15 The block 5 is provided on each side with the extensions 11, 12, 13 and 14 which form an integral part therewith and are used for the purpose of clamping the block to the exhaust pipe as will now be described.

20 Passing under the exhaust pipe is the strap 15 which may be made in one piece but is preferably made in 2 pieces to provide for adjustment. If the strap were made in one piece, straps of different lengths would have to be used to fit different sizes of exhaust pipes.

25 The ends of this strap are provided with the studs 16 and 17 which pass through the slots 18 and 19 that are formed between the extensions 11 and 12 on one side and extensions 13 and 14 on the other side. The nuts 20 and

30 21 are provided on the studs 16 and 17 by which the studs and the strap may be drawn up against the lower side of the pipe and the block 5 may be drawn down on the top of the pipe thus securely closing the opening 6 in the pipe.

35 Instead of making the strap 15 all in one piece I preferably make it in two pieces as shown in side elevation in Figure 3 and as shown in bottom plan view as shown in Figure 5. The part 15A is provided with a narrow tongue 22 which engages in one or the other of the series of slots 23 formed in the part 15B. By setting this tongue 22 in the slot forward or back and bending the tongue over, the strap can be

40 lengthened or shortened as may be desired and the two parts thereof may be securely fastened together. When the two parts are thus fastened the strap is put in place as shown in Fig. 3, the nuts may be turned drawing the strap and the block securely against the pipe and holding the pipes 1, 4 and the tube 3 firmly in place with relation to the exhaust pipe of the engine.

45 Washers 24 and 25 are placed under the nut 20 and 21 as are shown in Figure 3.

50 As I have shown in Figures 2, 3 and 4 a single U shaped tube is used therein and this pipe works very well for the purpose of heating a single radiator, but if this tube is connected up to supply steam to two radiators so that the steam is divided between them, it has been found in practice that one radiator will get more steam than the other and that the different parts of the car will be unequally heated.

To overcome this objection I provide in the exhaust manifold a single inlet water tube 30 and two outlet steam tubes 31 and 32 as shown in Figure 6. In such case the tubes 30, 31 and 32 are all connected to a thimble 33 into which all the tubes open with the tube 30 between the tubes 31 and 32. The water and steam will flow equally from the inlet tube 30 to the outlet tubes 31 and 32.

70 In Figures 7 and 8 I have shown the same kind of connection in which the U shaped tube is made of a flat tube having a rectangular cross section, it having been found that the tube can be bent upon itself and made more compact by installing it in this way. If desired a large tube of rectangular section can be used such as indicated at 34 and a partition 35 can be run down through the tube. The lower end of the tube will be closed with a cap. The water will pass down 80 one side of the partition 35 and the steam will pass up on the other side of the partition.

85 In Figure 9 I have shown one inlet water tube and four outlet steam tubes, the inlet water tube being the central tube as is indicated by the reference numeral 40 and the outlet tubes 41 are arranged around it so as to receive steam therefrom equally. In this case five tubes would be used as shown in the 90 cross section of Figure 10.

95 In some cases the end of the heating tube will vibrate in the exhaust pipe and is therefore apt to make a noise. To prevent this the exhaust pipe 7 is perforated with a suitable 100 hole and a hook 50 is passed into the hole and engaged with the heating tube. The lower end of the hook is threaded and a nut 51 is screwed up thereon to pull the hook and tube down into engagement with the pipe and hold it there.

105 I claim:

110 1. A coupling for a heating system comprising an exhaust pipe having a large hole therein, an apertured block adapted to cover said hole, fork extensions on each side of said block having an opening between them, a strap adapted to pass under the pipe opposite to said hole, said strap having a stud on each end thereof, nuts engaging with said stud by which the block and strap are drawn close against the exhaust pipe, the block closing the large opening in the pipe two openings in said block, a U shaped pipe extending through said openings, packing material on top of said block surrounding said U shaped pipe, a washer having two holes in it on top of said packing material, a ring cap threaded to said block and adapted to squeeze the packing material between the washer and the block and seal the joint between the block and the U shaped pipe.

115 2. A coupling for a heating system comprising an exhaust pipe having a large hole therein, an apertured block adapted to cover 120

said hole, fork extensions on each side of said block having an opening between them, a strap adapted to pass under the pipe opposite to said hole, said strap having a stud on each end thereof, nuts engaging with said stud by which the block and strap are drawn close against the exhaust pipe, the block closing the large opening in the pipe, a water tube and steam tube passing through said block and making close engagement therewith, said tubes extending into and lengthwise of the exhaust pipe and being connected together in the exhaust pipe so that water flows into said tubes on one side and steam flows out of the tube on the other side.

3. A coupling for a heating system comprising an exhaust pipe having a large hole therein, a block adapted to cover said hole, fork extensions on each side of said block having an opening between them, a strap adapted to pass under the pipe opposite to said hole, said strap having a stud on each end thereof, nuts engaging with said stud by which the block and strap are drawn close against the exhaust pipe, the block closing the large opening in the pipe, said strap being made in two parts one part of the strap being finished on its end with a narrow tongue and the other part of the strap having a plurality of openings therein, said tongue being adapted to pass through any one of said openings and being adapted to be bent over to lock the two parts of the strap together.

4. The combination of an exhaust pipe having a hole therein, a tube passing into said pipe through said hole and being bent on itself inside of the pipe and passing out again from said pipe through said same hole, a clamp adapted to hold the ingoing and outgoing ends of said tube in said hole and close the hole between the tube and the pipe, the ends of the tube being exposed outside of the pipe for the purpose of making connections therewith.

5. The combination of an exhaust pipe having a hole in the side thereof, a tube passing into said pipe and out again through said hole, said tube having a U-shaped portion within the pipe extending substantially parallel to the axis of the pipe, the free ends of said tube being bent at right angles to the U-shaped portion, both of said free ends passing out of said pipe through said hole, a clamp adapted to hold the free ends of said hole and close the hole between the free ends of the tube and the pipe, connections outside of said pipe with the free ends of said tube whereby liquid may be circulated through said tube and be heated by the exhaust gases.

In testimony whereof I affix my signature.
JAMES S. DOUGLASS, JR.
